DESIGN FOR A TOMBSTONE

Joseph E. Julius and Major H. Scroggins,
Youngstown, Ohio

Application June 25, 1936, Serial No. 63,497

Term of patent 14 years

To all whom it may concern:

Be it known that we, Joseph E. Julius and Major H. Scroggins, citizens of the United States, residing at Youngstown, in the county of Mahoning and State of Ohio, have invented a new, original, and ornamental Design for a Tombstone, of which the following is a specification, reference being had to the accompanying drawing, forming part thereof.

The single figure is a perspective view of a tombstone showing our new design.

We claim:

The ornamental design for a tombstone as shown.

JOSEPH E. JULIUS.
MAJOR H. SCROGGINS.
